UNITED STATES PATENT OFFICE.

STANLEY W. FINCH, OF WASHINGTON, DISTRICT OF COLUMBIA.

RAIL-TYING DEVICE.

Application filed February 12, 1927. Serial No. 167,782.

This invention pertains to rail-tying devices and more particularly to devices by means of which the rail and ties comprising the major units of a railroad track may be secured together.

The invention is shown in the accompanying drawings wherein:

Fig. 1 is a side elevation, partly in section, showing one form of my rail-tying device as it appears when used in attaching a rail to a tie.

Fig. 2 is a plan view partly in section, taken on the line *a—a* of Fig. 1.

Fig. 3 is a view, partly in section, taken on the line *b—b* of Fig. 2.

Fig. 4 is a perspective view of a rail-flange yoke forming part of the type of rail-tying device shown in Fig. 3.

Fig. 5 illustrates a method by which the yoke shown in Fig. 4 may be attached to a rail so as to act solely as an anti-creeping device.

Fig. 6 is a perspective view of a hook-like bolt forming part of the type of my device shown in various figures including Fig. 1.

Fig. 7 is a side elevation, partly in section, of a somewhat modified method of using my invention.

Fig. 8 is a view, partly in section, taken on the line *c—c* of Fig. 7.

Fig. 9 is a plan view, partly in section, taken on the line *d—d* of Fig. 7.

Fig. 10 is a perspective view of a slightly modified form of rail-flange yoke which is shown in various figures including Fig. 8.

Fig. 11 is a side elevation, partly in section, showing a further method of employing my invention.

Fig. 12 is a view, partly in section, taken on the line *e—e* of Fig. 11.

Fig. 13 illustrates a method by which the yoke shown in Fig. 10 may be attached to a rail so as to act solely as an anti-creeping device.

Fig. 14 is a side elevation, partly in section, showing a still further method of employing my invention.

Fig. 15 is a view, partly in section, taken on the line *f—f* of Fig. 14.

Fig. 16 is a plan view, partly in section, showing a still further method of employing my invention.

Fig. 17 is a view, partly in section, taken on the line *g—g* of Fig. 16.

Fig. 18 is a perspective view of a U-shaped tie-contacting member forming part of my invention as shown in Figs. 14 to 17 inclusive.

In the drawings 1 denotes a rail such as is employed as part of an ordinary rail-way track, said rail having a base or flange portion 2.

3 is a railway tie.

4 is a rail flange yoke (shown in perspective in Fig. 4) having at one end a hook-like portion 5 adapted to embrace the edge of the rail-flange 2, having at the other end a shoulder 6, and having adjacent said shoulder an opening 7 for the reception of either the shank of the hook-like bolt 8 (shown in perspective in Fig. 6) as in Fig. 1, or the bolt 9 shown in Fig. 5, or one arm of the U-shaped member 10 shown in Fig. 17 (also shown in perspective in Fig. 18). 75

11 is a washer.

12 is a nut surmounting a washer 11.

13 is a modified form of rail flange yoke, having at each end a shoulder 14 and having adjacent each of said shoulders an opening 15 for the reception either of the shank of the hook-like bolt 8, or the bolt 9, or one arm of the U-shaped member 10. 80

16 is a nut underlying one end of the yoke 4 or the yoke 13. 85

By means of my present invention a rail may be securely fastened to a tie at a relatively small cost and without removing or interfering with any of the spikes, fish plates, or tie plates already in use. Thus to 90 install the form of my device shown in Figs. 1, 2 and 3 it is necessary only to fit a yoke 4 under the rail flange adjacent each side of the tie, insert the shanks of two hook-like bolts with the nuts 16 mounted thereon 95 through the openings 7 in the yokes 4, place the hook ends of the hook-like bolts 8 under the adjacent edges of the tie 3, draw the parts together by means of the washers 11 and nuts 12, and when the desired tension is 100 secured, tighten the nuts 16 so as to lock the device permanently in position. This form of the device calls for the employment of but two hook bolts at each point where the rail rests on a tie, the bolts being placed alternately on opposite sides of the rail to 105 balance the strain thereon.

In Figs. 16 and 17 a somewhat similar arrangement of parts is shown, the U-shaped member 10, however, taking the place of the 110

two hook bolts 8 shown in Figs. 1, 2 and 3, the base portion of member 10 lying in a diagonal position under the tie 3 and the staggered arrangement of the tensioning means being maintained as in Figs. 1, 2 and 3.

In Figs. 11 and 12 the same general plan is followed as in Figs. 1, 2 and 3 except that the yoke 13 takes the place of the yoke 4, the bolt 9 with the attached washer and nut in conjunction with the adjacent shoulder 14 functioning somewhat like the hook-like portion of yoke 4.

In Figs. 7, 8 and 9 provision is made for two hook-like bolts, with each yoke 13, a similar type of my device being shown in Figs. 14 and 15 except that two U-shaped members are substituted for the four hook-like bolts of Figs. 7, 8 and 9. These two methods of employing my invention are, of course, substantially stronger than those shown in Figs. 1, 2 and 3 or 11 and 13, or 16 and 17 above mentioned but they also involve additional expense for material and installation.

Figs. 5 and 13 illustrate methods of employing the yokes 4 and 13 solely as anti-creeping devices without the employment of means (such as hook-like bolts or U-shaped members) for locking the rail to the tie. In this connection it should be noted that my invention, in all of the other forms illustrated, acts as an anti-creeping device as well as a rail-tying means since in each instance the yoke is locked securely to the under side of the rail flange and adjacent the side of the tie thus preventing the rail from creeping or moving longitudinally across the surface of the adjacent tie.

While to use my device in its most efficient manner it should be applied at each point where the rail rests on a tie, very beneficial results may be attained, and at proportionately less cost, by using the device on alternate ties or at even longer intervals if desired. Where the device is employed adjacent to rail joints it will be found advantageous to use yokes with relatively higher shoulders and deeper hooks than those illustrated so as to allow for the thickness of the base of the fish plate in addition to the thickness of the edge of the rail flange, thus providing for the clamping of the yoke to both the fish plate and the rail flange and consequently stiffening the rail joint.

One of the advantages of the use of the hook-like bolt as illustrated is facility of installation, it being necessary only to drive a bar down into the ballast along side of the tie at the desired point to make room for the insertion of the hook bolt claw under the tie; whereas, in order to insert the U-shaped member 10 under the tie it is necessary either to raise the end of the tie for the purpose or else to remove a considerable part of the

ballast lying beside and under the tie, thus causing increased expense for labor and also diminishing the stability of the roadbed. It thus appears that while the U-shaped members may well be employed in new railroad construction work, the use of the hook-like bolts is advantageous in applying my invention to existing railroad tracks.

It is well known that the present method of fastening rails to ties by means of spikes is unsatisfactory since the spikes quickly become loosened and must be frequently driven back into place to hold the rail to the tie. Moreover, each time the spikes are driven back into the same hole the friction which tends to hold them in place is reduced in amount until finally they become so loose that they can be pulled out by the hand. With my invention, however, no such result occurs, but, on the contrary, with each adjustment of the tensioning means the rail is bound tighter and tighter to the tie. Thus, when the hook-like bolt is used, the strain on the rails serves only to drive the spike-like hooks deeper into the ties—just the opposite of what happens when ordinary spikes are used.

For convenience of reference in claiming my invention the term "tie hook" is, when used, intended to apply to a hook-like device of the general nature of the lower end of the hook-like bolt.

While the tie hooking device is shown as penetrating the bottom of the tie it is, of course, within the scope of my invention if the said device be attached to the tie by means penetrating the side wall thereof instead of the bottom surface.

The employment of the two nuts 12 and 16 for the purpose of locking the tie-contacting elements 8, 10 or their equivalent to the rail flange is of special importance as a feature of my present invention. This is apparent from the fact that this feature provides means of holding the tie-contacting element rigidly in its proper position at all times. The nut 16 serves not only to hold the yoke in place but it also makes possible the locking of nut 12 in place so that it will not loosen even if the contact between the lower part of the tie-contacting means and the tie should, as a result of strain upon the rail, become loosened.

The washer 11 may, of course, be of the lock-washer type.

What I claim is:

1. A rail-tying means, including a tie-hook with an upstanding prong, for fastening a rail to a tie.
2. A rail-tying device comprising a hook-like means for grappling a tie, said means comprising a bolt-like shank and a relatively sharp upstanding prong portion.
3. A rail-tying device comprising a member having a hook with a relatively sharp

- end adapted to penetrate one of the faces of a tie.
4. A device for securing rails to ties, comprising a hook-like member with a relatively sharp portion adapted to penetrate a tie, and means whereby and in connection with the hook-like member the rail and tie may be fastened together.
5. A rail-tying device, comprising tie-contacting means having an element adapted to penetrate the tie at a point below the upper surface thereof, and means for fastening the tie-contacting means to a superimposed rail.
- 15 6. A device for fastening a rail to a tie comprising a hook-like member adapted to engage the under-side of the tie, and adjustable tensioning means intermediate the hook-like member and rail.
- 20 7. Means, including a plate having at one end an upstanding shoulder adjustably clamped across the lower surface of a rail flange and beside the tie on which the rail rests, for fastening the rail to the tie.
- 25 8. A rail-tying device comprising rail attachment means having at one end a jaw consisting in part of an upstanding shoulder adapted tensionally to grasp the adjacent edge of the rail flange; tie-contacting means; and adjustable tensioning means intermediate the rail attachment means and the tie-contacting means.
- 30 9. A rail-tying device comprising a rail attachment means adapted to extend across the lower surface of a rail flange, said means having at one end thereof means for clasping the adjacent edge of the rail flange and having adjacent the other end downwardly extending means adapted to be attached to a tie; and adjustable means whereby and in conjunction with the rail attachment means the tie may be tensionally fastened to the rail.
- 35 10. A rail-tying device comprising a rail attachment means adapted to extend across the lower surface of a rail flange, said means having at one end thereof means for clasping the adjacent edge of the rail flange and having adjacent the other end an opening for the reception of a bolt-like tie-contacting member; and tensioning means whereby and in conjunction with the rail attachment means and tie contacting member the tie and rail may be fastened together.
- 40 55 11. A rail-tying device comprising a yoke-like member adapted to extend under a rail flange, said yoke-like member having at each end means for embracing the adjacent edge of the rail flange, the embracing means at one end of the yoke-like member including a bolt-like member, said yoke-like member also having an opening therethrough adjacent one edge of the rail flange for the reception of the shank of the bolt-like member; tie-attaching means; and means whereby
- and in conjunction with the yoke-like member and the tie-contacting means the rail and tie may be fastened together.
12. A device for fastening a rail to a tie, comprising a yoke-like member adapted to contact the under side of a rail flange; means at each end of said yoke-like member adapted to embrace the adjacent edge of said rail flange; means adjacent one end of said yoke for locking the yoke to the rail flange; tie-attachment means extending from one end of the yoke-like member to a point beneath the tie; and adjustable tensioning means connecting the yoke-like member and the tie-attachment member.
- 70 75 80 13. A rail-tying device comprising a yoke-like member adapted to extend under a rail, said yoke-like member having at one end means for embracing the adjacent edge of the rail flange and having at the other end an upstanding shoulder, said yoke-like member also having adjacent said shoulder an opening adapted for the reception of a bolt-like member extending in part below the tie on which the rail rests and in part between said shoulder and the adjacent edge of the rail flange, the bolt-like member being threaded in its upper portion and carrying two nuts at one end thereof whereby and in conjunction with the yoke-like member and the bolt-like member the tie is tensionally fastened to the rail.
- 85 90 95 100 14. A rail tying device comprising means adapted to be fastened to a rail, a hook-like member adapted to engage a tie and intermediate adjustable tensioning means.
- 105 15. A rail-tying device comprising a bolt-like member having a hook with a point adapted to penetrate one of the lower surfaces of a tie and having at the other end rail-contacting means whereby and in conjunction with the bolt-like member the rail may be secured to the tie.
- 110 115 16. A clamping device comprising a plate adapted to extend under a rail flange, there being at one end of said plate means for encompassing the adjacent edge of the rail flange and there being at the other end of said plate an opening through which the bolt-like member extends, by means of which bolt-like member and the encompassing means the clamping device may be secured to the rail flange.
- 120 125 130 17. A clamping device comprising a plate adapted to extend across the under side of a rail flange, said plate having at one end means for attachment to the adjacent edge of the rail flange and having at the other end a portion extending beyond the adjacent edge of the rail flange, said extended portion having a shoulder, and an opening intermediate the shoulder and the edge of the rail flange for the reception of a bolt-like member by means of which the clamping means may be locked to the rail flange.

18. A clamping device for rails comprising a plate adapted to extend across the lower surface of a rail flange, said plate carrying adjacent each end thereof means for encompassing the adjacent edge of the rail flange, the said encompassing means at one end of said plate comprising an upstanding shoulder and a bolt-like member adapted tensionally to secure the clamping device to the rail flange.
19. A device for restraining the longitudinal movement of a rail across the surface of a subjacent tie, said device consisting of a plate adapted to extend across the under surface of the rail flange adjacent to one side of the tie, said plate having at one end adjustable tensioning means, including an upstanding shoulder, for clamping the plate to the rail flange and at the other end means for encompassing the adjacent edge of the rail flange.
20. A rail-tying device comprising tie attachment means having an upstanding threaded portion with a pair of nuts mounted thereon adapted to clamp a section of an adjacent rail flange therebetween.
21. A rail-attachment device consisting of a bolt-like member with a pair of nuts mounted thereon and adapted to clamp a section of a rail flange therebetween, and means for fastening said rail-attachment device to a tie.
22. A rail-tying device comprising a plate extending across the under surface of the rail flange, an opening through one end of said plate, a washer lying in part above the adjacent edge of the rail flange, an upstanding bolt-like member extending through the washer and also through an opening in the plate, tie attaching means connected with the lower portion of the bolt-like member, a pair of nuts mounted on said bolt-like member one of which nuts is above and the other of which nuts is below the washer, the plate and the adjacent portion of the rail flange, the entire device being adapted to fasten the rail to the tie in such manner that the tension can be adjusted at will by tightening or loosening the nuts on the bolt-like member.

In testimony whereof I have affixed my signature.

STANLEY W. FINCH.
